United States Patent Office

Des. 194,534

Patented Feb. 12, 1963

194,534

CASKET HARDWARE MEMBER

Lawrence L. Green, Elmwood Park, Ill.
(2130 W. Rice St., Chicago, Ill.)

Filed May 31, 1962, Ser. No. 70,359

Term of patent 14 years

(Cl. D19—2)

Fig.1

Fig.2

Fig.3

Fig.4

Fig.5

FIG. 1 is a top plan view of a casket hardware member showing my new design;
FIG. 2 is a front elevational view thereof;
FIG. 3 is a bottom plan view thereof;
FIG. 4 is a left-side elevational view thereof; and
FIG. 5 is a right-side elevational view thereof.

I claim:

The ornamental design for a casket hardware member, substantially as shown.
